AUTOMATIC APPLICATOR FOR LIQUID SHOE POLISHES AND THE LIKE

George A. Brown, Roselle, N. J.

Application July 16, 1940, Serial No. 345,781

4 Claims. (Cl. 15—134)

This invention relates to improvements in automatic applicators and more particularly to applicators for liquid polishes and dressings for shoes and the like in which the fluid flow from a reservoir is controlled automatically.

An object of the invention is to provide a simple device for the intended purposes which may be quickly and cheaply manufactured for large scale consumption.

Another object of this invention is the provision of an applicator which is adapted for applying liquid polish or dressing to the desired portions of shoes or the like of the multi-color type without smearing or overlapping other portions of the shoe requiring polish or dressing of another shade or type.

A further object of the invention is to provide a device having a novel type of guard which in one position of use serves to protect the fingers of a user and in another protects the applicator portion of the device and permits the latter to be carried safely in a pocket, bag or purse without any possibility of soiling the contents of such pocket, bag or purse.

Still another object is the provision of such construction of the guard as to minimize the possibility of its being lost.

The device is equipped with a reservoir member or barrel, a removable so-called suction cup unit closing the member or barrel and a guard member. It is a further object of this invention to provide improved construction of the suction cup unit so as to minimize danger of its accidental separation from the reservoir with consequent spillage of the reservoir contents.

Another object of this invention is the provision of a novel type of stand for the device which serves to retain the device during idle periods, but keeps the device always ready for instant use.

To the accomplishment of the foregoing and such other objects as may hereinafter appear, this invention consists in the novel construction and arrangement of parts hereinafter described, and then sought to be defined in the appended claims, reference being had to the accompanying drawing forming a part hereof and which shows, merely for the purposes of illustrative disclosure, preferred embodiments of the invention, it being expressly understood, however, that various changes may be made in practice within the scope of the appended claims without digressing from the inventive idea.

In the drawing, in which similar reference characters denote corresponding parts;

Fig. 1 is an elevational view partially in section

of one form of my device with parts separated for illustrative purposes.

Fig. 2 is a vertical section taken along line 2—2 of Fig. 1 and viewed in the direction of the arrows.

5 Fig. 3 is a perspective view of one form of sponge rubber applicator intended for use in the device of Fig. 1.

Fig. 4 is a perspective view of a modified form of suction cup unit with a sponge rubber applicator member of different form.

10 Fig. 5 is a perspective view of a further modified form of sponge rubber applicator which may be used with my device.

Fig. 6 is a partial sectional elevation similar to 15 Fig. 3, 1 showing a modified form of guard as applied to the device.

Fig. 7 is a fragmentary perspective view of a further modified form of guard member.

Fig. 8 is an elevational view of an applicator 20 of the form shown in Fig. 1 as carried in a desk stand member which latter is shown in vertical section, and

25 Fig. 9 is a partial sectional view of a modified form of suction cup unit applicable particularly to the neck of a bottle.

Referring now to the drawing, 10 denotes a reservoir tube or barrel adapted to contain black or colored lotions, liquid wax dressings, white shoe dressings, or other types of liquid polishes or dressings. This tube is preferably of some unbreakable plastic composition of any of the commercially available types and preferably is both transparent and colorless so that the user may ascertain the color and amount of the contents at 30 a glance, or it may be tinted corresponding to the color of the dressing or polish intended to be used therein.

One end 11 of this reservoir is permanently closed. The other end 12 is open and provided 35 with an annular outwardly extending bead or flange 13, formed in the present embodiment by bending or rolling the rim of the tube back upon itself as shown.

An annular anchoring depression or groove 14 40 extending inwardly of the tube and having a shoulder 15 is provided on the barrel adjacent the bead 13 and serves as will be presently described as a means of firmly anchoring the suction cup unit 20 to the reservoir tube.

45 The suction cup unit 20 comprises a hollow stem member 21 of resilient material such as rubber or the like having cork-like external form and adapted to fit into the mouth 12 of the reservoir in sealing relationship. An annular 50 integral bead or flange 22 is provided at the rear

edge of this stem member. This bead 22 is resilient and deformable and so admeasured as to yield during insertion of the stem 21 in the barrel opening. The stem member has sufficient axial length to permit the bead or flange 22 to ride past the depression or groove 14 in the reservoir upon insertion and to lock behind the shoulder 15 formed by said groove. As a result impositive engagement of the bead or flange 22 and the shoulder 15 occurs after insertion of the stem into the opening 12. Thus the suction cup unit 20 as a whole will be effectively prevented from sliding out of the reservoir barrel during use. The flange thus serves as impositive means for preventing accidental uncorking of the reservoir during normal usage and is more efficient than a simple frictional engagement between the stem and reservoir walls. Being of resilient material, however, the stem with its flange may be withdrawn from the reservoir for replenishing the fluid contained therein.

Rearwardly the hollow stem member has a wall or partition 23 completely closing the end thereof. This partition is provided with two spaced tapered bores 24 terminating in capillary holes 24' for a purpose to be presently described.

Integrally formed with the stem member 21, of the same material, and attached to its forward end is a suction cup member 25. This member has tapered end walls 26 flaring outwardly from the stem as shown in Fig. 1 and straight side walls 27 as shown in Fig. 2 extending parallel to the stem forming thus a suction cup which in the section shown in Fig. 1 has trapezoidal form and in the section shown in Fig. 2 (taken at right angles to that of Fig. 1) has rectangular form. The suction cup member 25 is so located and formed on the hollow stem as to leave a cylindrical space 27' between its inner base 28 and the partition 23. A shoulder 29 is provided externally at the junction of the stem 21 and cup member 25. This shoulder is adapted to abut the bead 13 of the reservoir when the stem is in its finally inserted position on the reservoir, the length of stem between shoulder 29 and flange 22 being admeasured to permit the required engagement of the latter behind the shoulder 15.

An applicator 35 of sponge rubber or other suitable applicator material is adapted to be carried by the suction cup member. This applicator in the form shown in Figs. 1 and 3 is a square rectangular parallelopiped of the required material. It is mounted in the suction cup member in such manner that its square faces 36 are parallel with the straight side walls 27 and two of its opposite corner edges 37 and 37' lie in the plane of the central longitudinal axis A—A of the suction cup member and extend perpendicular to said axis. Thus mounted, the side faces 38 and 39 of the applicator directly adjacent the corner edge 37 extend oppositely at angles approximately of 45° with the said longitudinal axis A—A and the side faces 40 and 41 extend substantially parallel to the tapered end walls 26 of the suction cup. The inner corner edge 37' extends slightly into the cylindrical space 27' without touching the partition 23. The two remaining corner edges 42 and 43 are entirely clear of the outer edges 25' of the suction cup member so that in use as will be presently described, either one of the side faces 38 or 39 may be used to apply polish without causing contact between the shoe surface and the edges 25'. This applicator is permanently attached to

the inner walls 26 and 27 of the suction cup member 25 by suitable cement or any other desirable manner.

5 A propeller member 50 comprising a piece of wire of copper or other non-corrosive material having parallel legs 50' and 50² is strung or looped through the applicator at 51. The legs extend from the applicator 35 through the chamber 27', the tapered bores 24 and the capillary openings 24' in the partition 23 and are looped together or bent towards each other at 52 to prevent withdrawal after mounting.

15 The diameters of the capillary holes 24' are only slightly in excess of the wire diameters. Thus the space between the wire legs and the capillary openings 24' is made just sufficient so that the fluid in the reservoir will not leak out due to the resistance set up by capillary attraction of the liquid around the small space. 20 This prevents liquid L from leaking out through the holes and the applicator 35. The tapered bores 24 have maximum diameters sufficiently admeasured to facilitate insertion of the legs 50' and 50² during the assembly of the device.

25 A guard member 60 is carried on the barrel. This guard member is cup or bell-shaped as shown and has an opening 61 at its closed end of a diameter sufficient to permit frictional sliding movement of the member longitudinally on the outside of the barrel 10. The cup or bell member has sufficient depth and diameter to surround completely the suction cup unit 20 when the bell is located at the mouth end of the reservoir with the bead 13 engaging the inner wall of the bell member around the opening 61.

30 The bell member mouth 62 is adapted to be closed by a removable cap 65. This cap may have suitable bayonet slots 66 in its side walls serving to engage bayonet pins 67 carried on the bell member. With the cap in place, the suction cup unit 20 is completely enclosed by it and the guard member and permits the entire device to be carried in a pocket, purse or handbag without danger of soiling by the reservoir 45 contents or fluid on the applicator.

35 In use the cap is removed and the guard member 60 slid back on the reservoir tube to the dotted position shown in Fig. 1 to expose the applicator and the suction cup. In this position, 50 the guard member having substantially larger dimensions than the reservoir serves as a protective apron to prevent contact of the user's fingers with the applicator or shoes and thus prevents soiling.

55 A convenient clip 70 carried on the reservoir tube serves to facilitate carrying of the device in the pocket in the manner of a fountain pen.

60 The guard member may have the modified construction shown in Fig. 6. Therein the end of guard member 60' is externally threaded at 71. The removable cap member 65' is internally threaded at 72 and may be removed or applied by screwing onto the threaded portion 71.

65 A further alternative construction of the guard member is shown in Fig. 7. Therein guard member 60² is provided with an annular groove or depression 73. The cap member is provided with internal lugs or projections 74 which snap into the groove 73 when the cap is forced over the mouth opening of the guard. The engagement is sufficiently impositive to permit removal of the cap during use of the device.

70 Guard members 60, 60' and 60² and the caps 65, 65' and 65² may be made of the same material as that of the reservoir tube 2 or of metal

such as aluminum or of any other suitable material.

The applicator members, too, may have different form from that shown in Figs. 1, 2 and 3. For example, as shown in Fig. 4, the applicator 35' may be in the form of a rectangular parallelopiped inserted into a suction cup 25^a in such manner that the applicator surface 68 is perpendicular to the longitudinal axis of the suction cup unit 20'. In such event the shape of the suction cup portion 25^a of the suction cup unit is modified to receive the changed form of applicator. The stem 21 and internal structure of the suction cup unit remain otherwise the same.

A further modified form of applicator 35² is shown in Fig. 5. This applicator is shown as cylindrical in form and is attached in a suitably shaped suction cup member 25^b with its longitudinal axis perpendicular to the longitudinal axis of the suction cup unit 20². The curved outer surface of this applicator is used to apply the polish or dressing. The other internal structure of the suction cup unit is substantially the same as of the others.

The operation of the device is as follows:

Assuming the reservoir 10 to be filled with polishing fluid L and the suction cup unit 20 in place as shown in Fig. 1, the cap 65 is removed from the guard 60 as shown and the latter slid backward along the reservoir tube 10 to dotted position to unsheathe the applicator sponge 35. The user then tilts the reservoir barrel to an angle of about 45° with the horizontal so that one of the applicator surfaces 38 or 39 is substantially horizontal. He presses this surface onto the shoe surface to be polished with a pumping motion, serving momentarily to partially compress the applicator. Such pumping action causes the legs of the propeller 50 to move inwardly dislodging any sediment or encrustation about the capillary openings 24'. At the same time air from the chamber 27' is forced through the capillary openings into the reservoir building up a slight back pressure at the end 11 of the reservoir. This back pressure forces liquid out through the openings 24' and into the applicator 35 where it is absorbed, moistening the latter. After a few pumping motions the applicator becomes sufficiently moistened with liquid from the reservoir to commence application thereof to the surface of the shoe. This application to the surface may be by a brushing or rotary motion of the surface 38 or 39 of the moistened applicator on the shoe. Since the outline of the flat surfaces 38 and 39 have sharply defined straight edges because of the parallel-opedip shape of the said applicator 35, the latter is capable of applying polishes neatly to definitely defined shoe areas which may differ in color from others adjacent. The 45° tilt of the applicator during use makes it convenient to manipulate the device since it may be held between the fingers in the manner of a pencil. Also, since the guard member 60 remains on the reservoir tube below the finger grasping point, the fingers are protected from being smeared with polish from the moist applicator 35. If the reservoir becomes empty, the suction cup stem 21 is removed from the reservoir 10, the latter refilled and the stem replaced as described and shown in Fig. 1. The impositive engagement of the flange 22 behind the shoulder 15 prevents dislodgement of the suction cup unit during the motion of the device during application of polish.

After the user has completed the polishing operations, the guard is again slid over the suction cup unit and the cap 65 replaced. It may now safely be placed in a purse or clipped in the pocket by the clip 70 ready for further future use. Since the guard and cap completely enclose the moist applicator, no dangers of soiling of the pocket or purse are present.

It is understood, of course, that if the applicators 35' or 35² are used instead of applicator 35, the holding angle of the device in use will differ from 45°, being substantially 90° to the horizontal if the applicator 35' is used and any desired angle if that of Fig. 5 is used. It is essential, too, that the applicator present at least one sharply defined edge like the edges of the faces 38 and 39 or the sharp edges of the surface 68 or the edges 69 of the applicator 35², so that such sharp edges can be used along the bordering lines of one of the multi-colored areas of shoes being polished. The form of applicator 35 shown in Figs. 1-3 has been found particularly effective and convenient for use. The edges of the surfaces 38 and 39 are all sharply defined permitting sharply defined polishing. The corner edges 42 and 43 too are clear of the outer end 25' of the suction cup. Thus the suction cup itself does not interfere with brushing or rotating applicatory motion during use and eliminates streaks in the surface being polished. Also, the convenient holding angle of 45° for the device as a whole makes it easy and quick to use.

The guard 60 normally remains upon the reservoir tube at all times. Its removal over the open end of the reservoir is prevented by the bead 13 while the clip 70 prevents its complete removal from the closed end of the tube. There is thus no likelihood of its being lost or misplaced. The cap 65 is the only part completely separated from the device as a whole. Since this is normally only removed temporarily during use, there is little danger of loss. The guard member and cap thus provide an effective safety feature which eliminate danger of soiling at all times.

In the event that the device is not required to be carried, the guard 60 and cap 65 may be eliminated and a suitable desk or bureau stand substituted. Such a stand 90 is shown in Fig. 8.

This stand or base 90 composed of any suitable material for example "Polystrene" molding material or other suitable plastic material, metal or the like comprises a well member 91 closed at its bottom 91' and open at its top 91². A conical annular flange 93 integrally formed with said well member extends downwardly and outwardly from the top edge of the well. The lower outer edge 93 of the flange terminates at substantially the same level as the bottom 91' of the well and with it forms the base of the stand. The maximum diameter at the lower edge 93 is sufficient to provide a low center of gravity for the base as a whole and to prevent tilting of the base when a complete device including its reservoir tube 10 are carried in the well. The depth and diameter of the well itself are so admeasured as to receive the entire suction cup unit 20 therein as shown in such manner that when inserted and released the reservoir tube rests against upper edge 91² of the well directly above the bead 13 while the applicator 35 rests both against the bottom 91' of the well and presses slightly against the side wall 91³ of the well. Sufficient wedging exists in the position shown to prevent the device from falling out of the stand. Since the applicator 35 is near the bot-

tom of the comparatively deep well, it retains its moisture content over a longer period of time than if exposed and is ready for instant use without much or any pumping action ordinarily necessary if the device is left exposed on a desk or table rather than in the stand. The stand thus not only is a convenience for desk or bureau use but has the added function of keeping the applicator moist during non-use by preventing rapid evaporation of dressing or polishing fluid thereon.

For those users who prefer a larger reservoir than that afforded by the tube 10, I provide a suction cup unit 120 embodying principles of this invention which may be applied directly to the bottle containing polishing fluids. This modification is shown in Fig. 9. Herein, 100 denotes a bottle provided with usual opening 101 and neck 102. The suction cup unit 120 adapted for insertion in the bottle neck in place of the usual stopper has a construction substantially similar to that of suction cup unit 20. It comprises a hollow stem member 121 of similar material having cork-like form and adapted to fit into the opening 101 and neck 102 of the bottle in sealing relationship. An annular bead or flange 122 is provided adjacent the rear edge of this stem member. This bead, which is resilient and deformable, is so admeasured as to yield during insertion of the stem into the neck 102. The stem member 121 has sufficient axial length to permit the bead or flange 122 to engage the bottle internally at the shoulder 103 formed at the junction of the neck and bottle proper. The purpose of this engagement is similar to that of the bead 22 and positively prevents dislodgment of the suction cup unit from the reservoir bottle during use. The suction cup member 125 integrally formed with or attached to the stem member 121 is similar in form to suction cup member 25 or has the different shape shown to receive the sponge rubber applicator 35. All other internal parts of the stem and the propeller member 50 are arranged as in the suction cup unit 20 and operate in the same way. The same type of applicator 35 as that shown in Fig. 1 may be used or one of the other forms shown in Figs. 4 and 5 or the like may be used. This particular type of suction cup unit is conveniently applicable to commercial bottles of polish or dressing and operates on the same principles as that applied to the reservoir tube 10.

The device may be used to apply liquids other than polishes or dressings to surfaces.

It is to be understood, of course, that various modifications in form and structure may be made without departing from the spirit of my invention. I do not therefore wish to be limited to the exact details shown and described.

What I claim is:

1. A device of the character described comprising a reservoir having a mouthed opening, an internally projecting shoulder in said reservoir adjacent said opening but at a point other than said opening, closure means adapted to be inserted into said opening and comprising a stem member whose length is greater than the distance of said shoulder from said opening, a suction cup member, an applicator member supported by said suction cup member, and a lat-

erally projecting flange on said stem member serving for impositive engagement with said shoulder when said stem member is mounted on said reservoir to prevent accidental dislodgment of said stem member from said reservoir during use.

2. A device of the character described comprising a reservoir having a mouthed opening, an integral internally projecting shoulder in said reservoir adjacent to but at a point other than said opening, a suction cup unit comprising a stem member adapted to be inserted in said opening, said stem member having a length greater than the distance from said shoulder to said opening, an applicator associated with said unit, and means on said stem member adapted to engage impositively with said shoulder of said reservoir to prevent accidental dislodgment of said unit from said reservoir during use of said device.

3. A device of the character described comprising a fluid reservoir having a mouth opening, an integral shoulder adjacent to said mouth opening but at a point other than said opening, and means carried by said reservoir for applying fluid therefrom to receiving surfaces, said means comprising a tubular stem inserted into said mouth opening, a flange member on said stem for impositively engaging with said shoulder in said reservoir to prevent accidental dislodgment of said stem from said reservoir, a suction cup member attached to said stem and an applicator carried in said suction cup member, said applicator being perforate and resilient and having applying surfaces with sharply defined edges whereby fluid fed from said reservoir to said applicator may be applied to surfaces having limited outlines adjacent said limited outlines without overlapping the latter, and means for automatically feeding fluid from said reservoir to said applicator.

4. A device of the character described comprising a fluid reservoir and means carried thereby for applying fluid therefrom to receiving surfaces having limited outlines, said means comprising a suction cup unit including a hollow stem member having cork like external form and provided with an annular bead at its end for impositive engagement with said reservoir, a suction cup member integral with said stem member, said suction cup member having tapering end walls flaring from the stem and straight side walls forming a suction cup which in one cross section has substantially trapezoidal form and in a second cross section has substantially rectangular form, a resilient applicator member having substantially parallel piped form mounted in said suction cup member so that faces thereof extend parallel to the said end and side walls of said suction cup member and other faces of said applicator extend oppositely at angles with the longitudinal axis of the said suction cup member and externally thereof representing sharply defined faces for the application of fluid from the reservoir to said receiving surfaces of limited outline, and means in said unit for providing fluid to said applicator from said reservoir through said unit.
